UNITED STATES PATENT OFFICE.

FERDINAND S. OPPENHEIM, OF NEW YORK, N. Y.

CONTAINER.

Application filed September 10, 1924. Serial No. 736,804.

This invention relates to packing and shipping boxes and cases. More particularly it is directed to containers or cartons constructed of corrugated paper board or the like material for packing and shipping delicate apparatus such as radio sets, meters, typewriters and the like.

An object of the invention is to provide a packing and shipping box of the character described particularly adapted to receive apparatus having projecting parts and including improved means for protecting and accommodating such protecting parts.

A further object of the invention is to provide an improved container or carton of the character described which is of a simple collapsible construction to permit shipping and storing thereof in "knocked-down" condition and which may be quickly and easily set up for use, relatively inexpensive to manufacture and efficient to a high degree for the purposes described.

Other objects of this invention will in part be obvious and in part hereinafter pointed.

Certain features herein shown and described are shown, described and claimed in my Patent #1,522,902 issued January 13, 1925, and accordingly are not claimed herein.

With the above exception, the invention accordingly consists in the features of construction, combinations of elements and arrangement of parts which will be exemplified in the construction hereinafter described and of which the scope of application will be indicated in the following claims.

Fig. 1 is a perspective view showing a packing and shipping box embodying the invention, parts of the box being broken away to show the interior construction;

Fig. 2 is a cross sectional view taken on line 2--2 in Fig. 1 showing the box closed and sealed with a radio set (shown in dot and dash lines) packed therein;

Fig. 3 is a perspective view of one of the side cushioning members or partition liners;

Fig. 4 is a perspective view of the top cushioning member.

Referring in detail to the drawing, 10 denotes an outer casing or shell of a packing and shipping box embodying the invention which may have any desired shape or design and may be made of fibre board, card board or the like material but is preferably constructed of corrugated paper board, the cellular structure of which has been found to

add greatly to the cushioning effect for the purposes described.

As seen in Fig. 1, the outer casing 10 is of collapsible construction and comprises 60 elongated side walls 11, end walls 12 and cover flaps 13, 14, 15 and 16, all preferably formed from a single sheet of material, cut, creased and folded to form the rectangular shaped shell 10, the cover flaps being adapted 65 to fold inwardly to form the top and bottom walls for closing the casing. When the flaps are folded into their closed position, they may be held in place by any suitable means, as for example a strip of adhesive tape 17. 70

Partition liners or cushioning members 18 are provided which are arranged against the side walls, end walls and the bottom. These may be substantially identical in construction, and as is seen most clearly in Fig. 75 3, each is preferably formed of a single sheet of corrugated paper board, cut, creased and folded to form a rectangular shaped body portion 19, end walls 20 and side walls 21, said side walls 21 having flap extensions 22 80 which are bent to extend within and adjacent the end walls 20 and held in position by suitable fastening means. The flap extensions 22 or other fastenings for the side and end walls to retain them in their relative positions may be omitted if desired, since it is apparent that when the members 18 are assembled within the casing 10 the structure is self-retaining. (See Fig. 2.)

It will be understood that the shipping 90 box is of suitable dimensions to enable packing the article or articles therein so as to substantially fill the space marked A in Fig. 2, and that the partition liners 18 are of proper design to completely cover the inferior sides and bottom of the casing 10 to the height of the contents, said liners 18 and contents preferably extending a substantial distance below the top of the casing for the purposes which will hereinafter appear. 100

Where the contents occupying space A (see Fig. 2), comprise a radio set having the usual series of dials, levers and other like control means which project beyond its enclosing cabinet, a novel form of top cushioning member 23 may be provided which accommodates the said projecting parts and acts to support and space the set from the top cover of the casing. 105

As seen from Figs. 1 and 4, the top cushioning member 23 is preferably constructed of a single sheet of corrugated paper board,

- cut, creased and folded to have a central rectangular shaped recessed portion 23^a on one side of said member 23 and recessed channelled edge portions 23^b, 23^c, extending along the sides and ends respectively of the opposite side of said member 23. The cushioning member 23 when inserted in the casing 10 as shown on Figs. 1 and 2 has its central portion positioned to accommodate projecting parts of the article to be packed therein and the upstanding side walls 23^d of the portions 23^b and 23^c serve to support and space the contents from the top of the casing.
- 16 In the practice of the invention, the side and end partition liners 18 are first placed in position in casing 10 and are held in their respective places by means of the bottom liner 18 as is clearly shown in Figs. 1 and 2. Having arranged these liners in position with their body portions spaced inwardly from the various walls of the casing, the radio set or other article to be packed is then lowered into place, the side wall of the set abutting against the walls of the liner 18 and being spaced thereby a substantial distance from the walls of the casing 10. With these parts in position, the cushioning member 23 is inserted in the top opening of the casing with the central recessed portion 23^a thereof arranged to enclose the various projecting parts, the member 23 being dimensioned to the proper height to fill the space between the top of the set and the top of the casing. The cover flaps are then folded into position and the casing sealed in any suitable manner as by means of a strip of adhesive tape 17.
- It will thus be seen that there is provided a device in which the several objects of this invention are achieved and which is well adapted to meet the conditions of practical use.
- As various possible embodiments might be made of the above invention and as various changes might be made in the embodiment above set forth, it is to be understood that all matter therein set forth or shown in the accompanying drawings is to be interpreted as illustrative and not in a limiting sense.
- Having thus described my invention, I claim as new and desire to secure by Letters Patent:—
1. A packing and shipping box comprising an outer casing having a separate parti-
- tion liner arranged therein for each of the sides, bottom and top walls of the casing, said liners forming a supporting structure in the casing adapted to protect and cushion the enclosed contents against damage during transportation, at least one of said liners being formed of a single piece of material folded to have a central recessed portion adapted to accommodate projecting parts of the contents, and longitudinally and transversely extending channel portions bordering said recessed portion, as and for the purpose described and specified.
2. A packing and shipping box adapted to support the contents in spaced relation to the sides, at least one wall thereof having a cushioning member formed with a central recessed portion on one side thereof adapted to accommodate projecting parts of said contents, and channelled portions recessed from the opposite side of said member to extend along the edges of the latter outwardly from said central recessed portion, the side walls between the central recessed portion and said channelled portions adapted to support and space the contents from said wall of the casing.
3. In a packing and shipping box, a cushioning member constructed of a single sheet of material, creased and folded to have a central rectangular shaped recessed portion on one side thereof adapted to accommodate projecting portions of the contents packed in said box, said member having the edge portion thereof bent and folded to form recessed channels, the side walls between the central recessed portion and said channels adapted to support and space the contents from one wall of said box.
4. In a packing and shipping box, a cushioning member constructed of a single sheet of material, creased and folded to have a central rectangular shaped recessed portion on one side thereof adapted to accommodate projecting portions of the contents packed in the box, and marginal recessed channelled portions on the opposite side of said recessed portion, the walls of the latter adapted to abut the contents packed in the box whereby said member serves to cushion and space said contents from one wall of said box.
- In testimony whereof I affix my signature.

FERDINAND S. OPPENHEIM.
